US00D666974S

(12) **United States Design Patent**
Marroquin et al.

(10) **Patent No.:** US D666,974 S
(45) **Date of Patent:** ** Sep. 11, 2012

(54) **Y-JUNCTION INTERCONNECT MODULE**

(75) Inventors: **Marco A. Marroquin**, Austin, TX (US);
Thomas P. Parker, Dallas, TX (US);
Stephen P. Wurmlinger, Scurry, TX (US)

(73) Assignee: **SolarBridge Technologies, Inc.**, Austin, TX (US)

(**) Term: **14 Years**

(21) Appl. No.: **29/375,595**

(22) Filed: **Sep. 24, 2010**

(51) **LOC (9) Cl.** 13-03

(52) **U.S. Cl.** D13/147

(57) **CLAIM**

The ornamental design for a Y-junction interconnect module, as shown and described.

DESCRIPTION

Cross-reference is made to co-pending U.S. Design patent application Ser. No. 29/375,599 entitled “Male Connector,” which was filed by Marco A. Marroquin now U.S. Pat. No. D644,610, and co-pending U.S. Design patent application Ser. No. 29/375,598 entitled “Female Connector,” which was filed by Marco A. Marroquin, now U.S. Pat. No. D644,609, each of which is incorporated herein by reference.

FIG. 1 is a top and front perspective view of a Y-junction interconnect module showing our new design;

FIG. 2 is a front elevation view thereof, with the rear elevation view being a mirror image of FIG. 2;

FIG. 3 is a top plan view thereof;

FIG. 4 is a bottom plan view thereof;

FIG. 5 is a first side elevation view thereof; and,

FIG. 6 is a second side elevation view thereof.

The broken line in the drawing views is included to show unclaimed environment only and forms no part of the claimed design.
